CONTINUOUS GAS MAKING PROCESS

Mathias Fränkl, Augsburg, Germany, assignor to
American Oxythermic Corporation, New York,
N. Y., a corporation of Delaware

Application August 2, 1930, Serial No. 472,553
In Germany December 2, 1929

9 Claims. (Cl. 48—203)

The invention relates to a process for the generation of gas. More particularly, it relates to a process in which the heat of the generated gas is retained for subsequent augmentation of the gas producing procedure, and includes correlated improvements and discoveries whereby the generation of gas from a fuel material is enhanced.

It is an object of the invention to provide a process for the generation of gas which is characterized by an improved heat economy and efficiency, and which may be readily conducted on a commercial scale.

A further object of the invention is to provide a process in which the heat of generated gases will be utilized to effect an increase in temperature of a body of fuel subsequently to be gasified.

Another object of the invention is to provide a process for the generation of gas in which heat losses are materially decreased, and which may be readily operated on a commercial scale.

In the known methods of gasifying coal, coke and similar fuels as heretofore practiced, the gases withdrawn, when dry carbon was being gasified, could not be brought much below 800° C. This resulted in a considerable waste of heat since for each kilogram of solid carbon in the coal or coke being gasified about 5 cubic meters of gas are generated with a waste heat content of about 1250 Cal.

In accordance with the present invention, marked heat economy is effected by introducing this greater part of this heat of the withdrawn gases into the layers of fuel in the generator and thus make it available for gasifying the fuel so that the addition of steam may be considerably increased for each kilogram of fuel.

This improved result may be secured according to the present invention by operating with oxygen or air together with steam which is conducted through a generator comprising two shafts or columns united at their bottom ends. In carrying out my invention, steam is introduced alternatingly at the top of a generator column and during passage through glowing fuel effects gasification thereof and then passes through a second column from the bottom toward the top thereof, so that the generated gas gives up its sensible heat to fuel contained in the second column. After a period of time the operation is reversed and the steam is introduced at the top of such second column whose fuel has been preheated by the previous current of gas, and the gas generated in said second column is caused to give up its heat to the fuel in the first column. The steam cools the column of fuel from the top toward the

bottom thereof, and at the same time becomes heated to the reaction temperature whereupon it gasifies the carbon by reaction therewith.

For a fuller understanding of the nature and objects of the invention reference should be had to the following detailed description taken in connection with the accompanying drawing in which is shown a gas generator consisting of two fuel chambers having a communicating channel at their base adapted for alternate and periodical flow of steam and in which the process of the invention may be effectively carried out.

The steam employed to gasify the fuel is caused to enter the generator alternately at the points *a*' or *a*'' at the top of the generator columns *A*' or *A*''. The steam travels down the column of fuel which has previously been heated to incandescence and during its passage through the glowing layers of fuel for example coal or coke effects gasification thereof. The gas then travels through the connecting channel *B*, passes upwardly through the fuel bed of the other column to which it gives up its sensible heat and finally is drawn off at *b*' or *b*'' at a temperature of less than 100° C.

Air or pure oxygen, or air which has been freed of the greater part of its nitrogen, is introduced through the valve *k*. When operating with oxygen the introduction of such gas is not continuous, for during the first third of each reversal period the glowing fuel in which has been stored the heat of the previous current of generated gas, and which has been heated at least at its bottom portion to about 1250° C., contains sufficient heat to react with the steam. It is only when this heat has been used up that oxygen should be introduced as otherwise the generator will become too hot during the first few minutes following each reversal. To accomplish such control of the inflow of the combustion supporting gas, each generator column is provided with a controller *m*' or *m*'' which is operative in response to the temperature of the column of glowing fuel column and controls an oxygen valve *o*' or *o*'' which is opened only when the temperature in the generator has fallen below about 800° C. The valves *o*' and *o*'' are fed by a reversible three-way oxygen valve *p* which is actuated together with the steam inlet and fuel gas outlet valves and is reversed simultaneously therewith, thus cutting off alternately the supply of oxygen to that one of the valves *o*' or *o*'' which is in communication with the generator column which has been heated by the immediately preceding current of generated fuel gas.

The fuel content of the generator column in which the steam, as stated, is introduced from above, becomes cooled from the top toward the bottom thereof, while the other column, through 5 which the generated gas is conducted on its way to a place of use or storage, becomes heated during this period from the bottom toward the top. After an interval of from five to ten minutes the direction of flow of steam and generated gases is 10 reversed, as also is the oxygen valve p , and the steam is caused to travel down the column which has just previously been preheated and cools the same from the top toward the bottom thereof while the fuel gases generated therefrom travel 15 through the other column and preheat the same from the bottom toward the top. It will thus be seen that each column operates alternately as a fuel gas generator and as a waste heat accumulator, and that such waste heat is effectively employed 20 to assist in the reaction between the steam and carbon. It will be noted that this quantity of heat, which is recovered from the escaping generated gases, operates to heat the bed of fuel without causing combustion of any portion of 25 such fuel as is the case when the fuel is heated up by blowing a charge of air therethrough.

The reversing of the currents of steam and gas may be accomplished automatically by means of a servomotor C operated by compressed air. 30 The steam enters alternately at f' or f'' into the valves g' or g'' ; the gas leaves the generators alternately at b' and b'' .

Various modifications may be resorted to within the scope of the appended claims without departing from the spirit of the invention. For example, the columns A' and A'' may be built as a single generator composed of two columns, or may be considered as two separate generators connected for reverse operation. Also, if desired, the valves b' , b'' and g' , g'' may be combined into single reversing valves which may be operated to withdraw the generated gases from, or feed steam alternately to one or the other of the columns. 35

45 The coal to be gasified as a rule contains a considerable amount of tar. The tar distills when this coal is heated, but again liquefies before leaving the generator when it contacts with a fresh charge of coal, because it can remain as a vapour only at a temperature higher than 300° C. It is however necessary to remove the tar from the generator while it is in the gaseous state. To this end the blowing time preceding reversal once or twice in about an hour is extended until 50 the gases being withdrawn have attained a temperature of from 400° to 500° C., whereby the tar contained in the fuel is evaporated. More particularly, in order to remove or vaporize the deposited tar, the passage of steam is continued, for example once every hour, in a given direction 55 through the generator for about five to ten minutes. Thereby the column through which the outgoing gases are passing will become warmer and the temperature at the outgoing end, or top, will be raised to from 300 to 500° C., which suffices to vaporize the tar. 60

65 Thus, if steam is passing through shaft A' generating gases therein, and the thus generated gases passing through the channel B and upwardly and out through the shaft A'' this direction of flow will be continued until the temperature at the top of the shaft A'' has been raised sufficiently to effect a vaporization of the tar. When the tar has been vaporized from the shaft 70 A'', the flow is reversed and continued in the re-

versed direction, that is, so that the generated gases are now passed out of shaft A' until the temperature at the top of shaft A' has been raised sufficiently to vaporize the deposited tar therefrom. 5

When the tar has been vaporized from both shafts, the normal alternate periodical reversal of operation is established and continued until such time as it may be desirable, or necessary again to vaporize deposited tar. 10

The foregoing procedure for the gasification of fuel possesses advantages which are the more noticeable the drier the fuel which is to undergo treatment. A particular advantage resides in that a much greater quantity of steam may be utilized than can be employed in the generators of the more simple type operating with air. This is due to the fact that the recovery of 1250 Cal. per kilogram which were previously lost when operating with air and which according to the 15 process of this invention employing an oxygen containing gas are for the greater part recovered and made available for gasification, permits an increase in the quantity of steam used from about 20 0.4 to about 0.8 kilograms per kilogram of carbon 25 gasified. 25

I claim:

1. A process for the generation of gas which comprises forming two columns of coke having a communicating channel at their bases, introducing steam into the top of one of said columns previously heated to reaction temperature whereby gases are generated, passing the gases so generated through the communicating channel and thence upwardly through the second column of 30 coke, withdrawing the gases from the top of said second column, alternately and periodically reversing in rapid sequence the flow of gases through said coke columns and maintaining the reaction temperature by partial combustion with 35 a gas enriched in oxygen.

2. A process for the generation of gas which comprises charging coke into a gas generator consisting of two columns in communication at their base, heating the coke in at least one of said 45 columns to reaction temperature, introducing steam into the top of said column and conducting the same downwardly through zones of increasing temperature whereby gases are generated, conducting the generated gases to the base of 50 the second column of coke and during such passage introducing thereinto an oxygen containing gas, passing the gaseous mixture upwardly through the coke in said second column, wherein it passes toward the top through zones of decreasing 55 temperature, whereby sensible heat of the gases is stored in the coke, and withdrawing the gaseous product from the top of the second column with alternate and periodical reversal in 60 rapid sequence of flow of the gases.

3. A process for the generation of gas by interaction between a solid fuel and steam which comprises forming two columns of a solid fuel, introducing steam at the top of one of said fuel columns wherein gas is generated by reaction between the fuel and the steam, passing the generated gas through the second of said fuel columns and withdrawing the same at the top thereof, introducing an oxygen containing gas at the 70 base of said columns whereby the reaction temperature is maintained, and alternately and periodically reversing in rapid sequence the introduction of steam and the flow of gases through 75 said fuel columns.

4. A process for the generation of gas by interaction between a solid fuel and steam which comprises forming two columns of a solid fuel having a communicating channel at their base, introducing steam at the top of one of said fuel columns wherein generation of gas is effected by reaction between said fuel and steam, conducting the generated gas through the communicating channel to the second of said fuel columns and withdrawing the same from the top thereof whereby fuel in said column is preheated by the heat of the generated gases, maintaining the reaction temperature of the fuel mass by partial combustion with an oxygen containing gas, and alternately and periodically reversing in rapid sequence the introduction of steam with respect to and the flow of gases through said fuel columns. 5
5. A process for the generation of gas by interaction between a solid fuel and steam which comprises forming two columns of a solid fuel, introducing steam into one of said columns at the top thereof wherein gas is generated by reaction between said fuel and steam, passing the hot generated gases through the other column of fuel 10 wherein heat of said gases is stored and the fuel therein preheated, maintaining said fuel at reaction temperature by partial combustion with an oxygen containing gas, and alternately and periodically reversing in rapid sequence the introduction of steam with respect to and the flow of gases through said fuel columns. 15
6. A process for the generation of gas by interaction between a solid fuel and steam in a gas producer having a plurality of shafts and a communicating channel at the base of said shafts, which consists in charging the shafts with coal and operating each shaft containing coal alternately and periodically in rapid sequence as a gas generator and as a waste heat accumulator 20 whereby sensible heat in generated gases is stored in said coal and utilized to aid the reaction subsequently taking place between said highly heated coal and introduced steam in which gases are generated, introducing an oxygen containing gas 25 into one of said columns and at intervals continuing the operation of a given shaft as a waste heat accumulator until the heat stored therein increases the temperature thereof sufficiently to vaporize deposited tar. 30
7. A process for the generation of gas by interaction between a solid fuel and steam, which comprises forming two columns of coal having a communicating channel at their base, introducing steam into the top of one of said columns pre- 35
- viously heated to reaction temperature whereby gases are generated, passing the gases so generated through the communicating channel, introducing a gas enriched in oxygen into the gas stream during passage through the communicating channel whereby a part of said gas is burned and thence conducting the hot gases upwardly through the second coal column, withdrawing the gases from the top of said column, alternately and periodically reversing in rapid sequence the introduction of steam into and the flow of gases through said columns of coal, and periodically continuing the withdrawal of gas from a given column until the heat stored therein raises the temperature thereof sufficiently to vaporize deposited tar. 40
8. A process for the generation of gas which comprises charging solid fuel into a gas generator consisting of two columns in communication at their base, heating the solid fuel in at least one of said columns to reaction temperature, introducing steam into the top of said column and conducting the same downwardly through zones of increasing temperature whereby gases are generated, conducting the generated gases to the base of the second column of solid fuel and during such passage introducing thereto an oxygen containing gas, passing the gaseous mixture upwardly through the solid fuel in said second column, wherein it passes toward the top through zones of decreasing temperature, whereby sensible heat of the gases is stored in the solid fuel, and withdrawing the gaseous product from the top of the second column with alternate and periodical reversal in rapid sequence of the flow of the gases. 45
9. A process for the generation of gas by interaction between a solid fuel and steam in a gas producer having a plurality of shafts which comprises charging the shafts with a solid fuel and operating each shaft containing solid fuel alternately and periodically in rapid sequence as a gas generator and as a waste heat accumulator whereby sensible heat in generated gases is stored in said solid fuel and utilized to aid the reaction subsequently taking place between said highly heated solid fuel and introduced steam in which gases are generated, introducing an oxygen containing gas into one of said columns and at intervals continuing the operation of a given shaft as a waste heat accumulator until the heat stored therein increases the temperature thereof sufficiently to vaporize deposited substances. 50
